(57) **CLAIM**

The ornamental design for a loom apparatus, as shown and described.

DESCRIPTION

FIG. 1 is a top perspective view of a loom apparatus showing my new design;

FIG. 2 is a top view of a loom apparatus showing my new design;

FIG. 3 is a bottom view of a loom apparatus showing my new design;

FIG. 4 is a side view of a loom apparatus showing my new design;

FIG. 5 is an opposite side view of a loom apparatus showing my new design;

FIG. 6 is a front view of a loom apparatus showing my new design;

FIG. 7 is a back view of a loom apparatus showing my new design;

FIG. 8 is a top perspective view of a second embodiment of the loom apparatus showing my new design;

FIG. 9 is a top view of the loom apparatus of FIG. 8 showing my new design;

FIG. 10 is a bottom view of the loom apparatus of FIG. 8 showing my new design;

FIG. 11 is a side view of the loom apparatus of FIG. 8 showing my new design;

FIG. 12 is an opposite side view of the loom apparatus of FIG. 8 showing my new design;

FIG. 13 is a front view of the loom apparatus of FIG. 8 showing my new design; and,

FIG. 14 is a back view of the loom apparatus of FIG. 8 showing my new design.

Any dashed/broken lines presented in the figures form no part of the claimed design.

1 Claim, 14 Drawing Sheets
